United States Patent Office

Des. 193,478
Patented Aug. 28, 1962

193,478

BUILDING BLOCK

Le Grand J. Mercure, 112 Ridgeway Ave.,
College Park, Ga.

Filed Oct. 25, 1960, Ser. No. 62,621

Term of patent 3½ years

(Cl. D18—2)

FIG. 1 is a rear perspective view of a building block showing my design.

FIG. 2 is a top plan view of the building block shown in FIG. 1.

FIG. 3 is a bottom plan view of the building block shown in FIG. 1.

FIG. 4 is a front elevational view of the building block shown in FIG. 1.

FIG. 5 is a rear elevational view of the building block shown in FIG. 1.

FIG. 6 is a left end elevational view of the building block shown in FIG. 1.

FIG. 7 is a right end elevational view of the building block shown in FIG. 1.

I claim:

The ornamental design for a building block, substantially as shown.
